UNITED STATES PATENT OFFICE.

ROBERT T. JOHNSTON, OF PLAINFIELD, NEW JERSEY, ASSIGNOR TO THE CAMPBELL PRINTING PRESS & MANUFACTURING COMPANY, OF NEW YORK, N. Y., A CORPORATION OF NEW YORK.

MECHANICAL MOVEMENT.

No. 905,436.

Specification of Letters Patent.

Patented Dec. 1, 1908.

Application filed February 13, 1904, Serial No. 193,429. Renewed March 26, 1907. Serial No. 364,647.

To all whom it may concern:

Be it known that I, ROBERT T. JOHNSTON, a citizen of the United States, residing at Plainfield, in the county of Union and State of New Jersey, have invented a new and useful Mechanical Movement, of which the following is a specification.

The object of this invention is to provide a new and improved apparatus for converting rotary motion into rectilinearly reciprocating motion.

To this end, this invention consists of the parts and combinations of parts as herein-after described and more particularly pointed out in the claims at the end of this specification.

In the accompanying six sheets of drawings, Figure 1 is a sectional view taken on the line 1—1 of Fig. 2. Fig. 2 is a sectional elevation taken on the line 2—2 of Fig. 1. Fig. 3 is a sectional elevation taken on the line 3—3 of Fig. 1, and Figs. 4 to 9 inclusive are diagrams on a reduced scale illustrating the different positions that the parts assume during the operation.

This invention has been designed as an improvement upon the mechanical motions which are disclosed in United States Letters Patent No. 570,586 granted in the name of Henry A. Wise Wood, Nov. 13, 1896, and in United States Letters Patent No. 570,597, granted Nov. 3, 1896 in the name of Winfield S. Huson.

The construction herein disclosed is primarily adapted for use as a bed-motion for printing presses, although it may be used in any location, and in any class of machinery in which it may be desired to produce forward and backward movement, and while I shall describe my invention as applied to printing presses, it is to be understood that I do not wish to be limited to this particular application of my invention. The printing press bed to secure the best results must be run at even speed during its forward and return strokes, and must be gradually stopped and started again in reverse directions without jar or vibration.

Broadly considered, an apparatus constructed according to this invention comprises mechanisms that will gradually retard the bed to a state of rest and then start the same in an opposite direction at a gradually accelerated speed, these reversing mechanisms being combined with a mechanism

adapted to give the bed the printing and return stroke at uniform speed, which latter mechanism will hereinafter be termed the main driving mechanism, while the other mechanisms will be termed the reversing mechanisms.

In printing press motions of the type disclosed in the Wood and Huson patents before referred to, the main driving mechanism comprises a driving pinion co-operating with racks for giving the bed its main forward and return motions. In the construction of these bed motions as actually employed the parts have been so timed that the driving pinion will make one complete turn for the main forward stroke of the bed; a half turn for the reversal at one end of the movement; a complete turn for the return stroke of the bed; and a half turn for the reversal of the bed at the other end of its movement. That is to say, to complete a cycle of operation in bed motions of this class as heretofore constructed the driving pinion makes three complete turns. Considering the times occupied in this class of bed motions as heretofore constructed, one-third of the time is given to a forward motion at uniform speed; one-sixth of the time is given to each reversal; and the remaining one-third of the time is given to the return stroke at uniform speed. In actual practice bed motions of this class can be run at high speeds and with great efficiency in the smaller sizes of printing presses.

In constructing the heavier and larger sizes of printing presses it has been found desirable to allow more time for reversals, and to shorten the periods allowed for the travel of the bed at uniform speeds.

In a mechanical movement constructed according to this invention, a two-revolution driving pinion is employed, and the parts are so timed that the driving pinion will make a half turn during the forward motion of the bed at uniform speed; a half turn for a reversal at one end of its movement; a half turn for the return stroke at uniform speed; and a half turn for the reversal of the bed at the other end of its movement.

A mechanical movement constructed according to this invention is characterized by the use of two distinct reversing mechanisms. In the specific construction illustrated two separate reversing pinions are employed. These reversing pinions are combined so

that their points of engagement will move oppositely with respect to each other.

Referring to the drawings for a detail description of an apparatus embodying this invention, 4 and 5 designate the usual side-frames of the printing press. On the side frames 4 and 5 the reciprocating bed or member 6 is mounted so as to reciprocate back and forth in any of the usual manners common in printing presses. The bed 6 has secured to the underside thereof a rack-frame 7, and on this rack-frame 7 are mounted the two parallel oppositely disposed driving racks 8 and 9. Secured to the underside 10 of the bed 6 is a frame or bracket 10 which carries the short rack 11 engaged by one of the oscillating pinions for reversing the bed at one end of its movement, as hereinafter described, and also carried by the frame or bracket 10 is a short rack 12 for engaging the other one of the oscillating pinions for reversing the bed at the other end of its movement as hereinafter described. Formed or fastened to the side-frame 4 is a bearing 13 or journal-box 13, and in this bearing and in a bearing 25 is mounted a shaft 15 which is the driving shaft of the machine, and on which may be mounted the usual tight and loose pulleys 16 and 17, by means of which power may be transmitted to the device. The tie-beam 20 connects the side-frames 4 and 5, and on this tie-beam is mounted a bracket 21 which has extending arms 22 and 23, with bearings 25 and 26 formed therewith. At their ends, the arms 22 and 23 are provided with slide-bearings, and in these slide-bearings are mounted the arms 30 of a reciprocating yoke 31. On the back of the yoke 31 is formed or fastened the rack 32, which rack 32 meshes with the underside of a gear 33 loosely mounted on the shaft 15, the gear 33 being held in place on said shaft between a collar 34 and the yoke 31, whereby said gear 33 is free to turn independently of the driving shaft 15 on which it is mounted. Mounted in the bearing 26 is a stud 40, and on this stud 40 is a gear 41 and pinion 70. The gear 41 is driven from a pinion 50 fastened on the shaft 15. The reduction between the pinion 50 and gear 41 in the particular construction shown is two to one. Fastened on the side of gear 41 is a bracket which carries a crank-pin 43. The crank-pin 43 is set on the pitch circumference of the gear 41, and this crank-pin 43 carries a block 42 fitted into the vertical slot 39 in the yoke 31. By means of this construction the yoke 31 will be reciprocated back and forth at a speed which is the resultant of a crank-pin movement, and thereby the gear 33 will be oscillated at proper speed to coöperate with the short rack 12, as hereinafter described, to reverse the motion of the bed at one end of its travel.

Fastened near the end of the shaft 15 is a

pinion 51 which meshes with a gear 52. The gear 52 is fastened on the shaft 53 which is journaled in an eccentric bushing 54. The gear 52 coöperates with the top and bottom racks 8 and 9 being the main driving pinion 70 through which the bed is given its main forward and backward reciprocations. The eccentric bushing has a flange 55, and as shown in Fig. 3, this flange has teeth 56 which mesh with teeth formed on the end of a lever 57, the lever 57 being pivoted on a stud 58 secured in the bracket 21. The pinion 70 upon the shaft 40 meshes into a gear 71 fastened on a shaft 81, which shaft 81 is journaled in the side-frames of the press. 80 Fastened on the shaft 81 is a cam 80. A yoke 61 is mounted on a square block 62 on the shaft 81, and the yoke 61 has rollers 63 and 64 which engage the cam 80. The cam 80 has two surfaces 82 and 83 connected by easy inclines. In making one revolution, the cam 80 will move the yoke 61 forward and backward. The motion of the yoke imparts a vibratory motion to the lever 57 which will oscillate the bushing 54 to raise and lower 90 the gear 52 to laterally engage the racks 8 and 9.

The parts as thus far described are substantially the same as those disclosed in the United States Letters Patent No. 570,586 to Henry A. Wise Wood before referred to, except that the main racks 8 and 9 are only one-half of the length of the corresponding racks shown in said Wood patent, while the reduction between the pinion 70 and gear 71 is two to one instead of three to one, and the reversing pinion 33 is wider than the rack 12 which coöperates therewith.

In the construction thus far referred to the gear 52 and racks coöperating therewith constitute the main driving mechanism, while the oscillating gear 33 and the short rack 12 constitute one of the reversing mechanisms for reversing the bed at one end of its travel. For reversing the bed at the opposite end of its travel, in the specific construction illustrated herein, I employ a second reversing pinion which meshes with and is driven from the reversing pinion 33. As shown most clearly in Fig. 1, a bracket 85 is bolted on to and extends up from the cross-tie 20. Extending from the bracket 85 is a stud 86, and journaled on the stud 86 is a second reversing pinion 87. The reversing pinions 33 and 87 mesh together for a part only of the width of their faces, one side of the reversing pinion 33 being left free to coöperate with the short rack 12, while the opposite side of the reversing pinion 87 is left free to coöperate with the short rack 11, the short racks 11 and 12 being secured out of line with each other for this purpose.

The operation of a complete mechanical movement as thus constructed can be most readily understood by a consideration of the 130

diagrams shown in Figs. 4 to 9 inclusive. Referring to said figures, in Fig. 4, the bed is shown as just completing its direct stroke to the left; the gear 52 just leaving the rack 8; and the oscillating gear 33 just engaging the rack 12 to commence the reversing movement. In this position the crank-pin is at its lowest point, and the yoke is moving to the right at a speed equal to the peripheral speed of the gear 52, whereby the gear 33 will properly engage its rack 12, and will move the bed to the left as a speed commencing at the maximum and gradually decreasing to zero as the crank 43 approaches the horizontal, or until the parts assume the position shown in Fig. 5. In other words, by a quarter revolution of the crank the bed is gradually retarded and brought to rest in a movement equal to the radius of the crank pin 43 or to the pitch radius of the pinion 52. During the next quarter revolution of the crank-pin the yoke will be moved to the left a distance equal to the crank radius at a speed gradually increasing from zero to the maximum, or until the parts assume the position shown in Fig. 6, the motion being transmitted to the bed by means of the rack 12 and oscillating gear 33. During this reversing action the cam 80 has oscillated the bushing 54 and the driving gear 52 has lowered to engage the rack 9. During the next half revolution of the driving gear 52 the bed will be moved to the right a distance equal to one-half the pitch circumference of the driving gear 52, or until the parts assume the position shown in Fig. 7. In this position the gear 52 is just leaving the rack 9 and the second reversing pinion 87 is turning in the proper direction to engage the short rack 11. During the next quarter revolution of the gear 52 the bed will move to the right under the control of the second reversing pinion 87 a distance equal to the crank radius at a speed commencing at the maximum and gradually decreasing to zero, or until the parts assume the position shown in Fig. 8, which is the right-hand extreme of the travel of the bed. During the next quarter revolution of the crank-pin 43 the reversing pinion 87 will move the bed to the left a distance equal to the crank radius at a speed commencing at zero and gradually accelerating to the maximum, or until the parts assume the position shown in Fig. 9. During the reversal of the bed by the reversing pinion 87 the cam 80 will oscillate the bushing 54 to raise the driving gear 52 so that the same will engage the rack 8 as shown in Fig. 9. During the next half revolution of the gear 52 the bed will be moved to the left a distance equal to one-half the pitch circumference of the gear 53, so that the parts will again assume the position shown in Fig. 4, completing the cycle.

In this mechanical motion, the driving gear 52 makes two turns for each cycle of operation in each direction, and a half turn for each reversal. That is to say, by using two separate reversing pinions, one for reversing the bed at each end of its movement, and which are crank-actuated, but which turn oppositely, I am enabled to provide a mechanical movement in which the time of each main forward and backward movement is the same as the time occupied for each reversal, and it follows from this that I have provided a simple and efficient form of two-revolution bed motion for printing presses, or for other purposes in which each reversal occupies one-quarter of the time of an entire cycle; whereas, in ordinary three-revolution bed motions, a reversal is only allowed one-sixth of the entire time of a cycle.

I am aware that numerous changes may be made in the operative parts of a mechanical movement by those who are skilled in the art without departing from the scope of my invention as expressed in the claims. I do not wish, therefore, to be limited to the constructions I have herein shown and described; nor, for reasons before stated, do I wish to be limited to the application of my invention to printing presses; but

What I do claim and desire to secure by Letters Patent of the United States is:—

1. The combination of a reciprocating bed or member, a main driving mechanism therefor, and two separate relatively oppositely moving reversing pinions, one for reversing the motion of the bed at one end of its stroke, and the other for reversing the motion of the bed at the other end of its stroke.

2. The combination of a reciprocating bed or member, a main driving mechanism therefor, and two separate reversing pinions, one for reversing the motion of the bed at one end of its stroke, and the other for reversing the motion of the bed at the other end of its stroke, said reversing pinions being driven so that their points of engagement turn relatively oppositely with respect to each other.

3. The combination of a reciprocating bed or member, a main driving mechanism comprising a driving gear and racks, and two separate reversing pinions, one for reversing the bed at each end of its stroke, said pinions being crank-actuated, and having their points of engagement with the bed moving relatively oppositely with respect to each other.

4. The combination of a reciprocating bed or member, a main driving mechanism therefor, a crank-actuated slide, and two independent reversing pinions relatively oppositely actuated from the slide for reversing the motion of the bed at the opposite end of its stroke.

5. The combination of a reciprocating bed

- or member, a crank-actuated slide, a reversing pinion mounted to oscillate on a fixed axis, a rack carried by the slide and meshing with the lower side of the reversing pinion, 5 and a second reversing pinion meshing with and driven from the first reversing pinion, said reversing pinions meshing with racks carried by the bed for reversing the motion of the bed at opposite ends of its stroke.
- 10 6. The combination of a reciprocating bed or member, a main driving mechanism comprising a driving gear, top and bottom racks coöperating therewith, means for raising and lowering the driving gear to coöperate 15 with the racks, and a crank-actuated independently-movable slide connected through two independent reversing pinions for reversing the motion of the bed at opposite ends of its stroke.
- 20 7. The combination of the reciprocating bed or member, a main driving mechanism

comprising a two-revolution gear and racks coöperating therewith to give the reciprocating bed or member its main forward stroke during a half turn of the driving gear, and to 25 give the reciprocating bed or member its main backward stroke during a half turn of the driving gear, a reversing pinion for reversing the movement of the bed at one end of its stroke during a half turn of the driving gear, and a second reversing pinion for reversing the movement of the bed at the 30 other end of its stroke during the last half turn of the driving gear.

In testimony whereof I have hereunto set 35 my hand, in the presence of two subscribing witnesses.

ROBERT T. JOHNSTON.
